OUTBOARD MOTOR

Douglas Ralph Clarke, Toronto, Ontario, Canada

Application June 5, 1936, Serial No. 83,745

8 Claims. (Cl. 115—18)

My invention relates to improvements in outboard motors, and the object of the invention is to devise an outboard motor which will be very compact and rigid, in which there will be no weaving action between the component parts thus eliminating power loss and repair costs commonly incurred, in which the cranking operation, the starting and warming up of the motor can be performed when the propeller is clear of the water and, therefore, requiring less effort to crank the driving motor and thereby rendering starting easier due to the absence of resistance of water to the propeller, in which better protection against damage is provided for the propeller when striking an obstruction and the use of shear pins which are difficult to replace eliminated, in which the use of gears to transfer power from a crank shaft to a propeller shaft is eliminated also eliminating the gear noise and reducing the consumption of the power generated, in which the suction of water into the engine through the exhaust is eliminated during the starting period, in which the carburetor is mounted above the fuel level thereby eliminating danger of fuel flooding the engine, in which the spark plug is cooled by the in-coming stream of fuel mixture passing over the spark plug boss and at the same time breaking up the heavy unvaporized particles of fuel by impinging them on the comparatively hot boss to form a more homogeneous mixture and producing a better engine performance especially at slow speeds, in which the cylinder and combustion chamber walls are cooled by direct contact with the water in which the propeller operates thereby eliminating extra water jacketing walls saving weight and cost of manufacture, and it consists essentially of the arrangement and construction of parts all as hereinafter more particularly explained.

Fig. 1 is a side elevation of my outboard motor showing it attached to a portion of a boat stern.

Fig. 2 is a vertical section through Fig. 1.

Fig. 3 is a plan section, the section being taken through the upper portion of the carburetor casing.

Fig. 4 is a sectional view on line 4—4 Fig. 2.

Fig. 5 is a sectional view on line 5—5 Fig. 2.

Fig. 6 is a sectional view on line 6—6 Fig. 2.

Fig. 7 is a sectional view on line 7—7 Fig. 2.

Fig. 8 is a sectional view on line 8—8 Fig. 2.

Fig. 9 is a side elevation of the distributing mechanism showing the drive shaft in section.

Fig. 10 is an enlarged fragmentary detail of the distributing mechanism as illustrated in Fig. 2.

In the drawings like letters of reference indicate corresponding parts in each figure.

1 indicates the fuel tank, 2 is an engine block provided at its upper end with a flange 3 secured by bolts 4 to the bottom wall of the fuel tank 1. 5 is a flange extending from the lower end of the engine block 2. 6 is a propeller carrying body which is connected to the flange 5 by means of bolts 7. By this means the fuel tank, engine block, and propeller carrying body are rigidly connected together to form a single unit.

7' is a clamping bracket provided with an arm 8 having an internally threaded boss 9, through which a threaded clamping screw 10 extends, the inner end of the screw being provided with a head 11 engaging the stern portion 12 of the boat, the head 11 being forced into position to clamp such portion by means of a handle 13. 14 is a short shaft extending through the side flanges of the bracket 7'. 20

15 is a vertical shaft preferably tubular which is secured in lugs 16 and 17 extending from the rear wall of the fuel tank 1. 18 is a member provided with lugs 19 and 20 through which the vertical shaft 15 extends and in which the shaft 25 is turnably held so that the outboard motor can be swung either to one side or the other for the purpose of steering.

21 is a lug extending upwardly from the top wall of the fuel tank 1 provided with an orifice 30 22 extending therethrough transversely of the outboard motor. 23 is a curved arm provided at its outer end with a handle 24, the inner end of the curved arm being inserted in the orifice 22 so that the outboard motor may be swung by the 35 steersman to either one side or the other.

The member 18 is also provided with a lug 25 of sleeve form having an orifice 26 through which the short shaft 14 freely extends permitting the outboard motor to be swung upwardly thereon on 40 a vertical plane when manipulated by the handle 24. 27 is a cam member provided with a notch 28 in its periphery. The cam member 27 is secured or formed integral with the lug 25 so as to swing therewith when the outboard motor is 45 swung in a vertical plane.

29 is a pin which is pivoted at 30 to the bracket 7', the free end of the pin extending through a slot 31 formed in the opposite wall of the bracket 7'. The pin 29 is held in its raised position by 50 means of a spiral spring 32.

When the outboard motor is swung to the raised position by depressing the handle 24, the cam member 27 is carried into engagement with the pin 29 forcing it downwardly against the ten- 55

sion of the spring 32 until the notch 28 is reached. The pin 29 is immediately carried into such notch by means of the spring 32 locking the outboard motor in the raised position. As shown in Fig. 3 5 the pin 29 protrudes beyond the bracket 7' at its free end so that when it is desired to release the outboard motor all it is necessary to do is to grasp the projecting portion of the pin and force it downward in the slot 31 out of engagement with 10 the notch 28 thereby freeing the outboard motor so that it will swing downwardly to its normal position.

33 is the engine cylinder formed in the engine block 2, 34 being the inlet port and 35 the exhaust 15 port. 36 is a carburetor of suction type enclosed in a casing 37. I do not describe this carburetor in detail as it is of a type commonly in use. 38 is a feed pipe by which the fuel is drawn up from the fuel tank into the carburetor. 39 is the inlet 20 manifold extending from the carburetor vertically through the fuel tank and connected at its lower end to a duct 40 leading to the inlet port 34.

41 is an igniter plug which is mounted in a hollow boss 42 which extends transversely of the 25 duct 40 so as to permit the vaporized fuel from the carburetor passing around each side of the boss as clearly indicated in Fig. 8 serving to keep it comparatively cool. 43 is a duct leading from the exhaust port 35 of the cylinder 33. In the 30 upper end of the duct 44 is screwed a coupling member 45 in which is secured a vertical tube 46 extending upwardly therefrom to a point above the water level.

47 is a tubular hood which extends over the 35 open upper end of the exhaust tube 46 and is secured in a stationary position by means of the straps 48 and 49 secured at 50 and 51 in the recessed wall of the fuel tank 1. The lower end of the tubular hood extends below the water level 40 so the exhaust gases from the exhaust port 35 of the engine are passed into the water.

52 is the piston of the engine operating within the cylinder 33 and provided with a piston rod 53. 6 is the propeller carrying body, the outer 45 surface of which is appropriately streamlined to pass easily through the water. 54 is the crank shaft of the motor journalled in bearings 55 and 56. The inner end of the crank shaft 54 is provided with a crank disc 57 having a crank pin 50 58 pivotally connected to the lower end of the piston rod 53. The outer end of the crank shaft 54 is provided with a tapered portion 59 on to which is driven a cylindrical boss 60.

61 is a sleeve. 62 are the propeller blades 55 which are formed integral with the sleeve 61. The sleeve 61 fits around the boss 60 against an annular rib 64. 65 are orifices formed in the periphery of the boss 60 and 66 are recesses formed in the inner periphery of the sleeve 61 60 and normally located in radial alignment with the orifices 65. 68 are spiral springs inserted in the orifices 65 and bearing against locking balls 69 which normally fit in the recesses 66. Normally the pressure of the springs 68 is sufficient to hold the balls 69 in engagement with the recesses 66 to form a driving engagement between the sleeve 61 and the boss 60.

Should one of the blades, however, strike an obstruction exerting an abnormal pressure 70 against such blades, the balls 69 will be forced inward out of the recesses 66 so as to permit the blades 69 and sleeve 61 turning freely around the boss, thus avoiding the breaking or damaging of the blade.

75 The boss 60 is locked upon the tapered por-

tion 54 of the crank shaft by means of a lock nut 70. 71 is a pulley member which is secured to the outer face of the boss by means of screws 72 suitably spaced apart.

When it is desired to crank the engine, the 5 outboard motor is swung upwardly by means of the handle 24 so that the propeller is carried clear of the water. A rope is then wound around the pulley member 71 and by pulling upon the 10 rope the pulley member is revolved so as to turn 15 the crank shaft 59 and thus crank the engine.

In order to advance or retard the spark I have 20 provided the following mechanism which I will now describe.

73 is a grooved member forming part of the 25 packing 74 of the crank shaft. 75 is an annular member provided with an annular tongue 76 fitting into the groove of the member 73 so that the annular member 75 is turnable concentric with the crank shaft 59. The crank shaft 59 is 30 provided with a cam projection 77 extending radially therefrom and adapted to engage a pivot arm 78 carried by the annular member 75 as indicated at 76. The upper end of the arm 78 is provided with a movable contact 79 coacting 35 with a stationary contact 80 carried by the annular member 75. 81 and 82 are lugs extending from the annular member 75 at diametrically opposite sides. The lug 81 is connected by a tension spring 83 to a pin 84 extending from any 40 suitable part of the propeller carrying member 6 as indicated at 85.

86 is a cable secured at one end to the lug 82. The cable 86 extends upwardly through the 45 engine block as indicated in Fig. 2 and through a tubular member 87 secured at its ends in the upper and lower walls of the fuel tank 1. 88 is a lug forming part of the carburetor. In the lug 88 is journalled a shaft 89. 90 is the operating shaft of the carburetor extending upwardly through an air inlet orifice 91 through which air is supplied to the carburetor. 92 is a hooded member secured to the upper end of the shaft so as to overhang the edges of the air inlet opening 91 as clearly indicated in Fig. 2. 93 is a cam secured 50 to the shaft 90. 94 is an arm bearing at its free end upon the operating surface of the cam 93 and secured at its opposite end to the shaft 89. 95 is an arm secured to the opposite end of the shaft 89, the free end of the arm being secured to the upper end of the cable 86.

By this construction it will be seen that by turning the hooded member 92 the operating shaft 90 of the carburetor is turned and at the same time the cam 93 is rotated so as to raise 55 the cam arm 94 and thereby rock the shaft 89 raising the arm 95 so as to pull upon the cable 96 and thereby rotate the annular member 75 and the pivoted arm 78 carried thereby around the shaft 59 carrying the arm 78 towards the 60 cam projection 77. By this means the spark is advanced, the cam 77 engaging the arm 78 so as to carry the contacts 79 and 80 apart.

When the hooded member 92 is turned in the opposite direction, the cam arm 94 swings down 65 on the surface of the cam 93 so as to release the pull on the cable 86 and allow the spring 83 to operate to turn the annular member 75 in the opposite direction to carry the arm 78 away from the cam projection 77 and thereby retard 70 the spark.

The stationary contact 80 of the distributor 75 is connected by a wire 96 leading to one terminal of a battery 97, the other terminal of such battery being connected by a wire 98 to the bind-

ing post 99 of the spark coil 100. The spark coil 100 is also provided with a binding post 101 connected to the opposite terminal thereof from which a wire 102 leads to ground. The spark coil 5 100 is also connected by a high tension wire 103 to a spark plug 41 as indicated in Fig. 2.

From this description it will be seen that I have devised an outboard motor which is very compact and rigid in construction, such outboard 10 motor consisting of three main parts namely the fuel tank, engine block and propeller carrying body which are rigidly connected together to form a single unit and thus eliminating any weaving action and wear between the component 15 parts, in which the cranking, starting and warming up operation of the motor may be performed while the propeller is clear of the water therefore requiring less effort to crank the motor at starting 20 eliminating the resistance due to the propeller revolving in the water, in which there is less liability for the propeller to become damaged when striking an obstruction, in which the driving gears for transferring power between a crank shaft and propeller shaft are eliminated over- 25 coming the consequent noise and substantially seven per cent of power loss, in which the suction of the water into the engine through the exhaust is eliminated and the danger of flooding the engine with fuel by mounting the carburetor 30 on the top of the fuel tank and in which the boss on which the spark plug is mounted is kept comparatively cool and is sufficiently hot to provide for the breaking up of hot particles of fuel impinging thereon and thereby producing greater 35 efficiency in engine performance.

What I claim as my invention is:

1. In an outboard motor, the combination with a submersible propeller carrying body, a fuel tank and an engine block interposed between and 40 rigidly connected to the fuel tank and propeller body, of a carburetor mounted on the fuel tank, an inlet duct extending from the carburetor through the fuel tank to the inlet port in the engine block, and a cupped igniter boss extending 45 transversely of the inlet duct and around which the cool incoming gases flowing through the inlet duct pass.
2. In an outboard motor, the combination with the propeller carrying body, engine block and 50 fuel tank rigidly connected together, a supporting bracket in which the tank is pivoted at its upper end and a steering arm, of a crank shaft journalled in the body, a pulley member secured to the outer end of the shaft around which a 55 rope is adapted to be wound, and means effective upon movement of the outboard motor to its raised position preparatory to the cranking operation to automatically lock the outboard motor in said raised position.
3. In an outboard motor, a supporting bracket 60 in which the upper end of the outboard motor is pivotally mounted to have a submerged lower end, of a normal horizontal cranking shaft journalled in the submerged portion of the outboard 65 motor, a crank mounted on the inner end of the shaft, means for driving the shaft, means at the outer end of the shaft for cranking the engine, a handle arm for swinging the submerged lower end of the outboard motor into a cranking position 70 above the water level, and means effective upon movement of the outboard motor to its

raised position preparatory to the cranking operation to automatically lock the outboard motor in said raised position.

4. In an outboard motor, a supporting bracket in which the upper end of the outboard motor is 5 pivotally mounted and having a submerged lower end, of a normal horizontal cranking shaft journalled in the submerged portion of the outboard motor, a propeller mounted on the outer end of the shaft, means for driving the shaft, means 10 at the outer end of the shaft for cranking the engine, a handle arm for swinging the submerged lower end of the outboard motor into a cranking position above the water level, means for releasably locking the outboard motor in the raised 15 position while cranking comprising a cam member secured to the pivot support of the outboard motor and provided with a peripheral notch, a spring pressed member carried in the supporting bracket depressed by engagement of the cam periphery to spring into locking engagement with the notch.

5. The combination with an outboard motor pivoted at its upper end to swing upwardly and including an internal combustion engine having 25 a submerged exhaust, a pipe extending upwardly from the exhaust above the water level, a tubular hood extending over the open end of the exhaust pipe and extending normally at its lower end or mouth to below the water level, which mouth is 30 adapted to rise above the water level when the outboard motor is swung to its upward position.

6. In an outboard motor, a propeller carrying body formed of a single integral unit having a central bore extending therethrough from end to end, bearings mounted in the bore, a crank shaft mounted in the bearings, a crank disc secured to one end of the shaft, a propeller secured to the opposite end of the shaft, and a closure insertable 40 in the bore of the propeller carrying body at the opposite end thereof to the propeller.

7. In an outboard motor, the combination with a submersible propeller carrying body, a fuel tank and an engine block interposed between and rigidly connected to the fuel tank and propeller body and containing an engine cylinder in the lower portion thereof having an inlet port and a duct leading from the top of the block to the inlet port, of a carburetor mounted on the fuel tank above the fuel level, and a tubular inlet duct 50 extending from the carburetor through the fuel tank to the duct of the engine body leading to the inlet port of the cylinder.

8. In an outboard motor, a propeller carrying body adapted to be supported below the water 55 level, an internal combustion engine having a crankshaft journalled in said body and having an exhaust conduit extending below the water level, a propeller driven by the crankshaft, a cranking disc connected to the crankshaft, means hingedly supporting the motor for swinging movement from a position wherein the propeller carrying body and the discharge end of the exhaust conduit is submerged below the water level 60 to a position wherein said body and discharge end of the exhaust conduit are exposed above the water level, and means for holding the motor in the last named position thereof during the cranking operation.

70
